EUGENE N. STROM, OF CHICAGO, ILLINOIS, ASSIGNOR TO PETTIBONE, MULLIKEN COMPANY, OF CHICAGO, ILLINOIS, A CORPORATION OF NEW YORK.

RAILWAY-CROSSING.

1,211,892.

Specification of Letters Patent.

Patented Jan. 9, 1917.

Application filed December 1, 1915. Serial No. 64,509.

To all whom it may concern:

Be it known that I, EUGENE N. STROM, a citizen of the United States, residing at Chicago, in the county of Cook and State of Illinois, have invented a new and useful Improvement in Railway-Crossings, of which the following is a specification.

My invention relates to an improvement in the class of cast-metal crossings (including frogs), and more especially those which, (or at least their portions of members on which the wheel-flange grooves intersect), are cast of hard metal, and more particularly manganese steel.

A crossing of the kind referred to is ordinarily cast in two similar parts, which are joined together at their abutting longitudinally-grooved rail-members by bolting the latter together through fish-plates. These parts are very large and heavy and unwieldy to handle. Moreover, imperfections occur more or less frequently in a casting in making it, requiring the entire part to be discarded, and these occurrences add materially to this already expensive practice of manufacturing the crossings. In the use of these crossings they are liable to become fractured by the pounding of wheels against the brittle corner-portions at the intersecting grooves for the wheel-flanges; and such damage to a crossing destroys the entire casting, requiring it to be replaced by a new one.

The primary object of my invention is to minimize this tendency to fracture, and at the same time to greatly reduce the expense of replacement in the event of fracture; and this I accomplish, generally stated, by so constructing the crossing as to form the corner-members, or parts on which the wheel-flange grooves intersect, as separable sections fastened together to yield, more or less slightly, under impact of the pounding referred to.

In the accompanying drawings, Figure 1 is a top plan view showing a preferred embodiment of my invention in a railway-crossing; Fig. 2 is an enlarged bottom plan view of one of the four corner-members of the crossing; Fig. 3 is a top plan view of the same showing the interfitting parts comprising a corner-member in disassembled relation, and demonstrating the manner of connecting therewith the respective railway-rail, and Figs. 4, 5 and 6 are enlarged sections respectively on lines 4, 5 and 6, Fig. 1.

The entire crossing shown in Fig. 1 comprises four similar hollow cast sections A and four similar angular corner-pieces B. Each section A is formed as a straight hollow rail-section 7 of the cross-sectional shape illustrated in Fig. 6 and containing a longitudinal wheel-flange groove 8 and having oblique faces 9 at their ends; and similar guard-rail sections 10 extend outwardly correspondingly on the opposite ends of each rail-section and contain wheel-flange grooves 8^a flaring toward their outer ends.

To construct a crossing with the four cast sections A, these are assembled by bringing the oblique ends 9 into meeting contact one with another, thereby producing the crossing in square form, as illustrated in Fig. 1, because each of these ends extends at an angle of forty-five degrees. The resultant formation also brings corresponding grooves 8 and 8^a properly into alinement. If the crossing is to be, say of rhombus shape, the angles of the oblique ends should, of course, be formed to extend accordingly. Into the angular space formed between each of two adjacent guard-rail sections 10 fits a correspondingly shaped corner-piece B, the sides of each being coextensive with the respectively adjacent guard-rail sections. Before adjusting the corner-pieces into place, rails C of the track for which the crossing is provided are applied thereto, by fitting against the outer face of each guard-rail section the end-portion of a rail and clamping it between that face and the opposing face of the respective corner-section. These opposing faces are shown to be provided with longitudinally extending ribs 11 to enter the opposite sides of the rails, the faces of these ribs being recessed at intervals, as shown, to form protuberances 11^a or "pads" to bear against the opposite sides of the web of the rail-end confined between them, the ribs also affording shoulders conforming to and fitting against the opposite under sides of the rail-head, as represented in Fig. 4. With the parts assembled as described, angular braces 12, conforming to the inner corners of the crossing, are fitted into them between the heads and flanges and against the webs of the adjacent rail-section 7, and the assembled parts are bolted together, as shown.

By the described sectional construction of the crossing, the track-rails C are not only held much more firmly by clamping each

between a guard-rail section and the adjacent side of a corner-piece B than in the ordinary construction of crossing, wherein the parts corresponding with these corner-
 5 piece sides are extended to enable the end-
 portion of a rail to be bolted to one recessed and therefore weakened side of the extension, but the construction enables these ex-
 10 tensions to be wholly omitted with the two-
 fold advantage of economy of metal and re-
 ducing weight, and the further advantage, by bringing the rails that much closer to
 the crossing, of reducing the extent of le-
 15 verage of the rails exerted against the cross-
 ing by trains in approaching and clearing it. This leverage also tends to fracture the crossing at and near the intersecting grooves when the metal has there become crystallized, as it does in time, under the pounding
 20 of traversing wheels; and by thus reducing the leverage, the tendency of its action to fracture the crossing is materially reduced.

The primary object of my invention, namely that of minimizing the tendency to fracture the crossing by impact in traversing it, of wheels passing over the intersections of the flange-grooves 8 and 8^a, is due to the yielding of the joints at 9, against which the wheel-pounding is directed, suffi-
 25 ciently to cushion the blows of the pound-
 ing wheels, because of the separate formation and bolted fastening together of the parts.

I realize that considerable variation is possible in the details of construction thus specifically shown and described, and I do not intend by illustrating a single, specific or preferred embodiment of my invention to be limited thereto; my intention being in
 30 the following claims to claim protection upon all the novelty there may be in my invention as broadly as the state of the art will permit.

What I claim as new and desire to secure
 35 by Letters Patent is—

1. A railway-crossing having corner-members formed with separably and yieldingly jointed sections having guard-rail sections formed thereon, and the joints extending
 40 diagonally through the wheel-flange grooves at their intersections.

2. A railway-crossing having its corner-
 members formed of jointed sections with
 45 guard-rail sections formed thereon and ex-
 tending therefrom, the joints of said sec-

tions extending diagonally through the wheel-flange grooves at their intersections and being yielding, and corner-pieces in the angles between adjacent guard rail sections.

3. A railway-crossing having corner-members formed of jointed sections with guard-rail sections formed thereon and extending therefrom, the joints of said sections extending diagonally through the wheel-flange grooves at their intersections and being yielding, and the corner-pieces in the angles formed by adjacent guard-rail sections, the opposing guard-rail sections and the corner-pieces forming confining means for the end portions of the track-rails between them. 60

4. A railway-crossing having corner-members formed of obliquely-jointed sections, the joints extending diagonally through the wheel-flange grooves at their intersections, guard-rail sections on said jointed sections 65 and corner-pieces in and fitting the angles formed by adjacent guard-rail sections, the opposing guard-rail sections and sides of the corner-pieces corresponding in length and forming confining means for the end- 70 portions of the track-rails between them. 75

5. A railway-crossing comprising straight one-piece cast rail-sections having oblique ends meeting in the corner-members of the crossing to form yielding joints extending 80 diagonally through the wheel-flange grooves at their intersections. 85

6. A railway-crossing comprising straight one-piece cast rail-sections having oblique ends meeting in the corner-members of the crossing to form joints extending diagonally 90 through the wheel-flange grooves at their intersections, and guard-rail sections on the opposite ends of each of said rail-sections.

7. A railway-crossing comprising straight one-piece cast rail-sections having oblique ends meeting in the corner-members of the crossing to form joints extending diagonally 95 through the wheel-flange grooves at their intersections, and guard-rail sections on the opposite ends of each of said rail-sections and corner-pieces in the angles formed by adjacent guard-rail sections, the guard-rail sections and corner-pieces forming confining 100 means for the end portions of track- 105 rails between them.

EUGENE N. STROM.
